COMBINED BOTTLE AND DISPENSER

John R. Crimmel, Hartford City, Ind., assignor
to Sneath Glass Company, Hartford City, Ind.,
a corporation of Indiana

Application August 27, 1948, Serial No. 148,323

Term of patent 7 years

(Cl. D58—6)

To all whom it may concern:

Be it known that I, John R. Crimmel, a citizen of the United States and a resident of Hartford City, in the county of Blackford and State of Indiana, have invented a new, original, and ornamental Design for a Combined Bottle and Dispenser, of which the following is a specification, reference being had to the accompanying drawing, forming a part thereof.

Figure 1 is a side view of a combined bottle and dispenser, showing my new design.

Figure 2 is an elevational view looking from the right of Figure 1.

Figure 3 is an elevational view looking from the left of Figure 1.

Figure 4 is a top plan view; Figure 5 is a per-

spective view; and Figure 6 is a bottom plan view.

I claim:

The ornamental design for a combined bottle and dispenser, as shown.

JOHN R. CRIMMEL.
